UNITED STATES PATENT OFFICE.

LEBOVICS MARTON, OF TERRE HAUTE, INDIANA.

RENDERING-TANK.

1,288,638.

Specification of Letters Patent. Patented Dec. 24, 1918.

Application filed September 27, 1918. Serial No. 255,945.

To all whom it may concern:

Be it known that I, LEBOVICS MARTON, a citizen of the United States, residing at Terre Haute, in the county of Vigo and State of Indiana, have invented certain new and useful Improvements in Rendering-Tanks; and I do hereby declare the following to be a full, clear, and exact description of the invention, such as will enable others skilled in the art to which it appertains to make and use the same.

This invention relates to rendering tanks or apparatus and has for its object to provide a means of this nature which will be comparatively inexpensive to construct, and more certain and simple in action than those which have been heretofore proposed.

With these and other objects in view the invention consists in the novel details of construction, and combinations of parts, more fully hereinafter disclosed and particularly pointed out in the claims.

Referring to the accompanying drawings forming a part of this specification in which like numerals designate like parts in all the views:—

Figure 1 is a vertical sectional view of an apparatus made in accordance with this invention;

Fig. 2 is a cross sectional view taken on the line 2—2 of Fig. 1, looking in the direction of the arrows;

Fig. 3 is a cross sectional view taken on the line 3—3 of Fig. 1, looking in the direction of the arrows;

Fig. 4 is a cross sectional view taken on the line 4—4 of Fig. 1, looking in the direction of the arrows;

Fig. 5 is a perspective view of the perforated press member detached from the apparatus; and

Fig. 6 is a diagrammatic detail perspective view of a portion of the parts shown in Fig. 5, illustrating the pivoting members 30 in their operative position.

1 indicates any suitable power pulley for rotating the shaft 2 and pinion 3 which meshes with the bevel gear 4 rigid with the nut 5, mounted on the press frame 6 supporting said shaft 2. Said frame is in turn supported by the standards 7, passing through the upper flange 8, and the lower flange 9 of the tank 10 provided with the bottom 11, and steam jacket 12 surrounding said bottom as shown.

Passing upwardly through said bottom and steam jacket is the short shaft 13 on the

upper end of which are mounted the rotating knives 14. Below said jacket is mounted on said shaft 13 the bevel gear 15 meshing with the pinion 16 carried by the shaft 17 on which is mounted the power pulley 18, as shown. 20 represents a steam inlet and 21 a steam and water outlet.

Fitting the interior 25 of the tank 10 are the vertically disposed ribs, rods or spacers 26 made of any desired form, and rigid with the perforated vertically moving press member 27 leaving a space 28 between its outer surface and the interior 25 of the tank 10. Said perforated press member is conveniently made in two parts hinged together as at 28', which are outwardly flared as at 29 to fit the interior 25 of the tank 10, for a purpose that will presently appear. Near the lower edge of the press member 27, and on the interior thereof, are located the lifting members 30 hinged to the interior of the member 27 as at 31, see Fig. 6. Said lifting members 30 are capable of being swung up into the positions shown in Figs. 1 and 5, or they can be swung down as shown in Fig. 6, whereupon their right angular extensions 33 will contact with the member 27 and hold the lifting members 30 in their horizontal positions.

Around the top rim of the compressor member 27 are the turned over lips 35, beneath which are located the disk like lifting and compressing member or press plunger 36. Said plunger member 36 is secured to the screw 37 which passes upwardly through the nut 5, and which may not rotate. On top said lips 35 contact with the holding or clamping member 40 through which said screw 37 also passes, and which is held in its clamping position by the nut 41. 42 represents a vent or gas escape pipe; while 43, 44, 45 and 46 represent pipes for carrying off water and grease, the last two passing through the steam jacket 12 as illustrated.

In addition to said pipes 43, 44, 45 and 46, I provide a plurality of pipes 46' which I call cookers. These pipes 46' are preferably three in number, only one being shown, and their function is to supply live steam to the meat and cook the same as will be readily understood. In addition to supplying steam through said cookers 46' I may also supply live steam through the pipe 46 by means not shown when the latter is not carrying off water and grease.

50 represents a cover for the tank 10, con-

veniently hinged as at 51, and provided with the handle 52. The operation of my invention will be clear from the foregoing but may be briefly summarized as follows:—

5 After operating the shaft 2 to lift the press member 27 entirely out of the tank 10, either whole carcasses or portions thereof may be placed in said tank whereupon the materials are subjected to the 10 action of the knives 14 while the cover 50 is closed and steam is turned on. After the meat material has been thus cooked, the cover 50 is lifted, the pulley 1 reversed and the press lowered to force out the fats from 15 the mass. During the lowering of the press member 27, its flanges 29 fitting the interior of the tank will press down the cooked material, and will force any bones or other like solids toward the center, thus enabling 20 the said flanges 29 to substantially reach the bottom of the tank 10.

The placing of animals or other material into the tank 10 is or may be facilitated by locating the flange 8 of said tank flush with 25 a sloping surface 75 of a floor as indicated in Fig. 1. In other words, the animals may come directly from the skinning or dismembering floor, and be thrown directly into the tank 10.

30 It is an important feature of the invention that the steam jacket 12 is located on the outside of the tank 10 instead of on the inside, for its outside location enables one to provide a continuous smooth interior 35 of the tank for the press to traverse, and therefore, to greatly increase its capacity over what the latter would be if the jacket 12 is located on the inside of said tank.

While the member 27 is descending the 40 hinged lugs 30 occupy the positions shown in Figs. 1 and 5, but when the press is ascending they automatically assume the position shown in Fig. 6, and thus enable the press to lift out of the tank the cooked compressed mass.

After the flanges 29 reach the bottom of the tank the clamping member 40 may be turned by any suitable means to one side to clear the lips 35, whereupon a continued 50 motion of the pulley 1 will cause the plunger 36 to descend independently of the member 27 and thus to compress the cooked material to any desired degree. During the above described operations, the fats, etc., that 55 have been expressed from the cooked material will pass through the perforations 55 in the member 27. The fluids passing through the perforations 55 will enter the spaces 28 and pass down to the bottom of the tank, to be forced through the pipes 45 and 46. But, the grease during the close 60 of the operation will of course mainly pass through the pipe 46. After all the grease has been thus recovered the cooked and 65 pressed material may be lifted by again re-

versing the pulley 1, in the manner above disclosed, through the agency of the hinged members 30. Should the operator desire to dry this mass of cooked material he may thus lift it to a suitable position, break it up 70 and let it fall back into the tank and there thoroughly dry it. Or he can, while it is in its compact form, lead it onto trucks and carry it away.

The handling of the compressed material 75 is facilitated by reason of the member 27 being hinged. That is to say, when said member containing said material is raised sufficiently above the flange 8, a truck may be backed over said tank with its wheels 80 resting on said flange on each side of said tank, and the member 27 holding said compressed materials may now be opened out, or turned on its hinge whereupon said material will drop into said truck and be carted 85 away. In case it is desired to dry the compressed material, or materials, it may be conveniently dumped back into the tank 10 from the truck, whereupon the cover 50 may be closed and steam turned into the jacket 90 12. While the material is drying it is best to continuously rotate the cutting and agitating device 14, and this said device 14 may also be rotated to force the material out of the opening 65.

95 It will be observed that I have left a considerable space 77 between the bottom of the tank and the bevel 15 so that said bevel may lift against the weight of the parts when the cutting means 14 strikes a bone 100 and thus disengage its teeth from the driving pinion 16. After passing the obstruction said bevel and pinion automatically re-engage under the action of gravity.

105 It will now be clear that with an apparatus of the nature of that disclosed, I am enabled to recover a much larger percentage of grease than would be possible if no press were employed; and that it takes much less fuel to dry the compressed mass, deprived 110 of its grease and water than it does to dry it when containing said water and grease. 65 represents an opening through which the tank 10 may be entered near its bottom and 66 represents a suitable closure for said opening.

115 It is obvious that those skilled in the art may vary the details of construction as well as the arrangement of parts without departing from the spirit of the invention, and therefore, I do not wish to be limited to the above disclosure except as may be required by the claims.

120 What I claim is:—

1. In a rendering tank, the combination 125 of a tank body provided with a chamber around the lower outside portion of the same; means to admit steam into said chamber and body; a cover for said body; a perforated, hinged press member contacting at 130

its bottom with the smooth interior of the tank body and adapted to be raised and lowered inside said body; means to space said press member from the interior surface of said body; and cutting means located in said body, substantially as described.

2. In a rendering tank, the combination of a tank body provided with a chamber around the lower outside portion of the same; means to admit steam into said chamber and body; a cover for said body; a perforated press member provided with an outwardly extending flange contacting with the smooth interior of and adapted to be raised and lowered inside said body; a plunger movable up and down in said press member; means to space said press member from the interior surface of said body; cutting means located in said body; and means for rotating said cutting means, substantially as described.

3. In a rendering tank the combination of a tank body provided with a smooth interior from top to bottom and a chamber around the lower outside portion of the same; means to admit steam into said chamber and body; a cover for said body; a perforated press member provided with an outwardly flared lower edge fitting said interior, and adapted to be raised and lowered inside said body; means to space said press member from the interior surface of said body; and cutting means located in said body, substantially as described.

4. In a rendering apparatus the combination of a vertically disposed tank having a smooth interior from top to bottom; a perforated press member having a flared lower edge adapted to fit said interior and to move from the top to the bottom thereof; a press plunger associated with said press member; means for raising and lowering said press member and plunger relative to said tank; means for cutting up the material on the inside of said tank; and means for admitting steam to the interior of said tank, substantially as described.

5. In a rendering apparatus the combination of a vertically disposed tank having a smooth interior; a perforated press member having a flared lower edge adapted to fit said interior; a press plunger associated with said press member; means for raising and lowering said press member and plunger relative to said tank; hinged means associated with said press member adapted to lift the compressed material from said tank; means for cutting up the material on the inside of said tank; and means for admitting steam to the interior of said tank, substantially as described.

6. In a rendering apparatus the combina-

tion of a vertically disposed tank having a smooth interior; a perforated press member comprising two parts hinged together having a flared lower edge adapted to fit said interior; a press plunger associated with said press member; a clamping member associated with said plunger and press member; means for raising and lowering said press member and plunger relative to said tank; means for cutting up the material on the inside of said tank; and means for admitting steam to the interior of said tank, substantially as described.

7. In a rendering apparatus the combination of a vertically disposed tank having a smooth interior; a perforated press member having turned over lips on its upper edge and having a flared lower edge adapted to fit said interior; a press plunger associated with said press member; means for raising and lowering said press member and plunger relative to said tank; means comprising hinged members carried by said press member for causing the compressed material to be lifted out of said tank with said press member; means for cutting up the material on the inside of said tank; and means for admitting steam to the interior of said tank, substantially as described.

8. In a rendering apparatus the combination of a tank having a steam space on its exterior; means for admitting steam to said tank and space; means for cutting up material placed in said tank; a perforated press member adapted to be raised and lowered relatively to said tank; a press plunger adapted to be raised and lowered relatively to said tank; a clamping member adapted to cause said plunger and press member to rise and fall together; and means comprising a screw for raising and lowering said plunger and press member, substantially as described.

9. In a rendering apparatus the combination of a tank having a steam space on its exterior; means for admitting steam to said tank and space; rotary means for cutting up material placed in said tank; a perforated press member provided with a flared lower edge, spaced from the interior of the tank, and having turned over lips on its upper edge adapted to be raised and lowered relatively to said tank; a press plunger adapted to be raised and lowered relatively to said tank; a clamping member adapted to cause said plunger and press member to rise and fall together; and means comprising a screw for raising and lowering said plunger and press member, substantially as described.

In testimony whereof I affix my signature.

LEBOVICS MARTON.
